US00D910023S

(12) United States Design Patent (10) Patent No.: US D910,023 S
Ahn (45) Date of Patent: * Feb. 9, 2021

(54) CASE FOR ELECTRONIC DEVICES

- (71) Applicant: SPIGEN KOREA CO., LTD., Seoul (KR)
- (72) Inventor: Deok Hyun Ahn, Seoul (KR)
- (73) Assignee: SPIGEN KOREA CO., LTD., Seoul (KR)

() Term: 15 Years(21) Appl. No.: 29/703,054(22) Filed: Aug. 23, 2019*Related U.S. Application Data

- (63) Continuation of application No. 29/647,283, filed on May 11, 2018, now Pat. No. Des. 860,212.
- (51) LOC (13) Cl. 14-02
